AUXILIARY PRINTING MECHANISM

Max Garbell, Chicago, Ill., assignor to Victor
Adding Machine Company, Chicago, Ill., a cor-
poration of Delaware

Application April 13, 1934, Serial No. 720,397

19 Claims. (Cl. 101—93)

This invention relates to an auxiliary printing unit and is illustrated as being attached to an adding machine with the printing portion thereof aligned in the printing line for making an impression simultaneously with those of the type bars actuated during the operation of the machine.

A unit of this kind is shown as mounted adjacent one side of the type bars of the adding machine and is adapted to move into and out of the printing line being yieldingly retained in normal retracted position and readily engageable by means of links and levers extending into the path of the unit and the operating mechanism of the adding machine.

15 The printing portion of the unit as shown will print a serial number and the date, but these characters may be changed, as they form no part of the present invention other than to be automatically adjusted with each operation of the machine while others of the characters are manually adjusted.

20 The chief objects of the invention are the provision of a printing unit having adjustable elements, some of which have characters, while others have digits thereon and which are mounted to move in a path with the unit for an impact against a platen or other suitable backing member and to be automatically restored and retained in a normal at-rest position, being also provided with a feeding mechanism which automatically adjusts some of the printing elements with each operation of the unit.

25 A further object is the provision of an actuating or tripping mechanism adapted to engage the unit for moving the same against the tension of its spring which draws the unit for an impact against the platen or backing member as the tripping mechanism is released therefrom in the normal operation of the machine, and said unit being provided with a yieldable retaining means which normally withholds the same out of the path of the platen or backing member after the impact thereof against said platen or backing member.

30 A still further object is the provision of a movable engageable member carried on the unit which is yieldingly retained into the path of the actuating or tripping mechanism which when engaged thereby, will cause a normal outward movement of the unit against the tension of its spring for causing an impact of the digits and characters when released against the platen and wherein the said engageable means will yieldingly ride over and again restore itself for engagement by the 35 tripping mechanism with each operation of the

machine by means of the normal tension exerted by a yieldable means which serves in the capacity of restoring the unit and for positioning the feeding mechanism thereof readily operable with each operation of the machine.

40 And a still further object is the provision of manually operable means for positioning and retaining the engageable means out of the path of the tripping mechanism so as to be ineffective therewith to render the unit inoperable with said tripping mechanism during the driving operations of the machine; to provide means for bodily adjusting the unit longitudinally of the platen or backing member whereby the printing elements may be spaced at various distances with respect to the type bars of the adding machine, and wherein also, the inking ribbon is automatically and simultaneously adjusted with the unit providing an inking means therefor.

45 Referring to the drawings:—

Figure 1 is a top plan view of the type bar portion and ribbon spool plate of an adding machine with my printing unit mounted thereon by means of a supporting plate extending outwardly on one side thereof and on which the unit is mounted to 50 slide adjacent the type bars.

Figure 2 is a face elevation view taken substantially on the line 2—2 of Fig. 1 looking in the direction of the arrows.

Figure 3 is a side elevation illustrating the ribbon spool plate with my device mounted thereon and the actuating mechanism therefor connected to the operating mechanism of an adding machine.

Figure 4 is an enlarged cross-sectional view taken on the line 4—4 of Fig. 1 showing the yieldable means for holding the unit in retracted position and in dotted lines as yielding for an impact of the unit against the platen.

Figure 5 is an enlarged detail cross-sectional view taken on the line 5—5 of Fig. 1.

Figure 6 is an enlarged detail cross-sectional view similar to Fig. 5 illustrating the device as being retracted and in engagement with the platen in dotted lines.

Figure 7 is an enlarged side elevation of the U-shaped rockable member illustrating the openings therein into which the pins extend to connect the arm thereto for actuating the same.

Figure 8 is an enlarged detail cross-sectional view taken on the line 8—8 of Fig. 1 illustrating the adjustable means for the unit supporting plate.

Figure 9 is a partial detail view of a portion of the ticket illustrating the characters printed.

thereon by means of my unit and the type bars of the adding machine.

The reference numeral 10 designates the ribbon spool plate or base which is common construction 5 in adding machine design and on which the ribbon spools 11 and 12 respectively are mounted being supported on the vertically extending spool shafts 13 and 14 and secured thereto by means of the thumb nuts 15 and 16 respectively. These 10 ribbon spools 11 and 12 are arranged in side by side relation for the purpose of providing a double ribbon across the face of the usual type bars of the adding machine and my improved unit which is adapted to coact therewith for simultaneous 15 printing with the type bars. The ribbon 17 as shown, extends from the ribbon spool 11 over a guide roll 18 fixed to the ribbon spool plate 10 and to a guide roll 19 which is fixed to the adjustable supporting plate 10a and the rollers 18 20 and 19 form a guide for the ribbon therebetween on opposite sides of the type bars and my improved unit. The ribbon 17 then folds back upon itself and is guided in parallel relation with its other portion by means of a guide roller 20 arranged on the supporting plate 10a adjacent the roller 19 and which guides the same to the roller 21 fixed in the ribbon spool plate 10 adjacent the roller 18 and guides the ribbon to the ribbon spool 12. Many forms of double ribbon arrangement 30 may be employed with a unit of this type, as it is more commonly used for the purpose of printing in duplicate, providing an original slip or ticket and having a record strip for recording the amounts which have been printed on the slips or 35 tickets. In illustrating this form of ribbon inking means, I also show a reversing mechanism indicated as a whole as 22 which is provided with a pair of compression springs 23 and 24 surrounding the respective vertical ribbon spool shafts 13 and 40 14 for exerting a frictional tension to the turning movements of these shafts to insure a taut parallel ribbon across the printing face of the type bars and my improved unit.

The type bars of the adding machine are designated as a whole as 25 having the usual hammers 45 26 which are common in their construction being operable by means of the hammer actuating shaft 27 which has a bifurcated arm 28 fixed thereto into which a stud 29 of a bell-crank 30 extends. The bell-crank 30 is pivotally supported for rocking movements on a stud 31 fixed to the side wall 32 of the adding machine and has its other leg 33 provided with a bifurcated portion 34 adapted to be engaged by a stud 35 fixed to an arm 36 which is 50 carried on a stud 37 fixed to the side wall 32 of the adding machine. The arm 36 is operatively connected to the driving mechanism of the adding machine (not shown), and intermittently engages the bell-crank 30 for actuating the hammers as the machine is operated.

My improved unit designated as a whole as 38, 55 is mounted for sliding movements on a plate 10a adjustably secured on the ribbon spool plate 10 and extends outwardly and adjacent one side of the type bars of the adding machine. The frame of the unit 38 is U-shaped as viewed in end elevation (Fig. 2), and has a bottom wall 39 and integral upwardly extending side walls 40 and 41. The bottom wall 39 has a plurality of studs 42, 43 60 and 44 fixed thereto that extend downwardly through elongated slot openings 45, 46 and 47 respectively in the adjustable supporting plate 10a. These slot openings 45, 46 and 47 are arranged to 65 guide the unit in its sliding movements on the supporting plate 10a and the shoulders 42a, 43a

and 44a on the respective studs 42, 43 and 44 serve as spacers and provide a three point contact for the sliding movements of the unit on the supporting plate 10a. The side walls 40 and 41 of the frame of the unit 38 are provided with a pair of 70 aligned transverse openings through which the shafts 48 and 49 extend. The shaft 48 carries a plurality of rotatably mounted printing elements or carriers 50 and 51 which are provided with suitable indicia thereon and are arranged in groups 10 as shown with the first three elements 50 adjacent the side wall 40 arranged to be manually adjusted by means of a stylus, while the remaining four elements 50 and 51 are provided with a toothed integral ratchet-wheel 52 adapted to be engaged by means of retaining members 53 which are 15 automatically adjusted with the movements of the unit for accumulating a serial number. Each of the elements 50 and 51 are provided with a toothed integral ratchet-wheel 52 adapted to be engaged by means of retaining members 53 which are 20 silently held therewith by means of flared finger springs 54 secured at 55 to a horizontally extending member 56. The member 56 has a downwardly extending portion 57 at each end thereof which is welded or otherwise secured at 58 to the side 25 walls 40 and 41 of the unit 38.

The printing elements 51 are each engaged by means of a ratchet feed dog 59 which also coacts with the integral ratchet-wheel 52 of these elements and are carried by means of a U-shaped 30 rockable member 60 supported for rocking movements on the printing element shaft 48. The U-shaped member 60 has an arm 61 fixed thereto outwardly of the side wall 41 by means of the pins 62 and is carried for rocking movements 35 with the U-shaped member 60 on the shaft 48. The pins 62 extend through arcuate slot openings 63 in the side wall 41 of the unit and fit into corresponding openings 62a in the leg 60a of the U-shaped member 60. The arm 61 is 40 normally urged upwardly by means of a torsion spring 64 having its body portion coiled around the free end of the shaft 48 and outwardly of the arm 61, with one leg of said spring engaging a roller 65 fixed to the free end of the arm 45 61 and with its other leg extending downwardly and through an elongated slot opening 66 in the adjustable supporting plate 10a and normally engaging a pin 67 fixed to the side wall 41 of the unit 38. The pin 67 forms a permanent 50 abutment for the downwardly extending leg of the torsion spring 64 which causes its other leg to elevate the arm 61 by means of its engagement with the roller 65 thereof.

The roller 65 of the arm 61 is normally retained in sliding contact with a cam surface 68 of a cam member 69 fixed to the supporting plate 10a and while the unit is being moved by means of the actuating mechanism which will be presently described, the roller 65 will ride on the cam surface 68 of this cam member 69 and cause a downward rocking movement of the arm 61 which will cause a partial turn of one of the elements 51. Upon a reverse movement of the unit 38, the torsion spring 64 will again 65 restore the arm 61 and as the movement of the unit is repeated, a step by step feed of the elements 51 will be had so as to sequentially change the serial number of each record made. This partial turn or step by step feed of the elements 70 51 is not new and it is thought that a brief statement of the operation will suffice for the operation thereof with my improved unit.

The operating mechanism for the device comprises an engageable arm 70 fixedly secured to 75

a stud shaft 11 which is slidably mounted for longitudinal sliding movements in a bushing 11a pivoted in the side wall 32 of the adding machine. The stud shaft 11 is provided with a keyway 11b adapted to be engaged by means of the depending arm 70a which is secured to the bushing 11a and by reason of the keyway 11b the arms 70 and 70a are rockable together as a unit with the stud shaft 11. The depending arm 10 70a has its lower end portion provided with a bifurcated opening 12 into which a roller 13 extends and which is fixed on the bell-crank 30 by means of the stud 14. The free upper end 15 75 of the arm 70 extends through an elongated slot opening 76 in the supporting plate 10a and through a corresponding aligned slot opening 77 in the bottom wall 39 of the unit 38. The upper end 75 of the arm 70 extends into the path of a yieldably mounted movable member 78 carried 20 25 for rocking movements on the shaft 49 between the side walls 40 and 41 of the unit 38 and is provided with a transversely extending portion 79 adapted to be engaged by the free upper end 75 of the arm 70. The movable member 78 is provided with outwardly extending arms 80 and 81 on each side thereof which are provided with aligned bored openings 83 through which the shaft 49 extends and on which the member 78 is adapted to rock being normally 30 35 held in position into the path of the end 75 of the arm 70 by means of a tension spring 82 fixed to the arm 81 thereof and to the cross-member 56. The arm 80 of the movable member 78 is provided with a roller 84 carried on a 35 40 stud 85 which is fixed to the free end thereof and which is adapted to normally rest into a recess 86 provided in the edge of an upwardly extending arm 87 pivotally carried on the shaft 49 adjacent the extending arm 80 of the movable member 78. The arm 87 is adapted to be moved manually and is retained in either its normal or changed position by means of a spring 88 fixed to the bottom wall 39 of the unit and has its free end portion 89 extending upwardly 45 50 and formed to fit one or the other of a pair of notches 90 in the arm 87. This spring 89 offers a sufficient tension to withhold the arm 87 in either its normal or changed position and when moved, by rocking the same downwardly, as 55 shown in dotted lines (Fig. 5), the notched-out portion 86 of the arm 87 will engage the roller 84 and cause a downward swinging movement of the extending arm 80 and a rocking movement of the movable member 78 and raise the transversely extending portion 79 thereof out of the path of the engaging end portion 75 of the arm 70, so that as the machine is actuated, the portion 79 will be out of the path of the end 75 of the arm 70 and a movement of the unit 38 60 will not be effected.

The unit 38 is adapted to be spring-impelled for an impact against the platen A of the adding machine and a tension spring 91 is attached to the depending portion of the stud 44 of the unit 65 and to a stud 92 fixed to the underside of the supporting plate 10a. The effect of this tension spring 91 is to normally retain the unit 38 adjacent to and retracted from the platen A of the adding machine, for as shown, the tension of the spring 91 is very light when the device is in its normal at-rest position (Fig. 5). The spring 91 coacts with the torsion spring 64 in retaining the unit in its normal at-rest position (Fig. 4), 70 and tends to retain the downwardly extending

leg of the spring 64 into engagement with the end 66a of the elongated slot opening 66.

As thus far described, it will be noted that as the machine is actuated, a rocking action of the arms 70 and 70a will be had and each rocking action of these arms will cause the unit 38 to be moved away from the platen A by means of the engagement of the end 75 of the arm 70 with the transversely extending portion 79 of the movable member 78 carried on the shaft 49. 10 Each movement of the unit 38 caused by the rocking action of the arms 70 and 70a with their pivot stud 71, will cause the unit to be carried a given distance against the tension of the spring 91. The rocking action of the arm 70 and 70a 15 will cause the end 75 of the arm 70 to automatically disengage the abutting portion 79 of the movable member 78 which will permit the unit to be free thereof for a return driving movement under the tension of its spring 91. This return 20 action of the unit 38 under the tension of its spring will be instantaneous upon the release of the end 75 of the arm 70 therewith and the speed with which the unit is being carried under the tension of the spring 91 will cause the downwardly extending leg of the torsion spring 64 to engage the end 66a of the slot opening 66 and yield thereagainst to permit the printing elements to strike the platen A with an impact, and by reason of the normal tension of 30 the torsion spring 64 against the end 66a of the slot opening 66, the unit will again be restored to its normal at-rest position under a very light spring tension exerted by the spring 91 until the restoring action of the depending leg causes the 35 pin 67 to again engage this depending leg of the spring 64.

As the unit is being moved as above described, the roller 65 of the arm 61 will be caused to ride on the cam surface 68 of the cam member 69 and cause a rocking movement of the arm 61 and a step by step feed of the elements forming serial numbers with each impact of the unit against the platen A of the adding machine.

The double inking ribbon arrangement is for 45 the purpose of double printing with one impact of either the printing unit or of the type bars of the adding machine and for that purpose I provide a guard 93 adapted to be carried on the paper table B of the adding machine for guiding 50 the usual paper strip C which is fed around the platen A by means of paper feed rolls D of the adding machine and which with my improved unit may provide a permanent record of the impressions made on the cards or tickets that are 55 positioned in front thereof to receive the direct impact of the unit and the type bars and through which the record is made. The guard 93 may be supported on the paper table B by means of screws 94 and provides an opening 95 therein for 60 the insertion of the card or ticket to be printed.

The supporting plate 10a for the unit 38 is carried on the ribbon spool plate 10 and is adjustable thereon so as to position the unit adjacent to or away from the type bars of the adding machine. This adjustment is for the purpose of positioning the unit so as to meet the requirements of the various types of tickets that may be used with a unit of this kind. The ribbon spool plate 10 is formed with a depressed portion 70 75 extending parallel with the surface thereof on which the supporting plate 10a rests and on which it may be slidably adjusted. The supporting plate 10a is provided with an elongated slot opening 10c aligned with a companion slot open- 75

ing 10d provided in the extension 10b of the ribbon spool plate 10 and has a rivet 10e extending through these slot openings for retaining the supporting plate 10a slidably movable on the ribbon spool plate 10.

In order to lock the supporting plate 10a on the ribbon spool plate 10, I provide a depressible button or knob 10f fixed to a member 10g which has a depending stud 10h—10h at each end 10 thereof and which are provided on their free end portions with a shoulder 10i—10i adapted to extend into enlarged openings 10j in the extension 10b of the ribbon spool plate 10. These shoulders 10h—10h are urged and retained in 15 the enlarged opening 10j by means of the compression springs 10k—10k interposed between the supporting plate 10a and the member 10g. These enlarged openings 10j in the ribbon spool plate 10 are interconnected by means of a slot 20 opening 10l extending the entire length of the enlarged openings 10j, forming a continuous opening with these enlargements to permit of the sliding movements of the stud 10h—10h therein. When the requirements are for a 25 larger ticket, or where the printing of the characters carried on the unit are to be spaced a greater distance from those of the type bars of the adding machine, the same may be accomplished by simply depressing the thumb portion 30 10f which will compress the springs 10k—10k and force the shoulders 10i—10i of the studs 10h—10h out of the enlarged openings 10j in the ribbon spool plate 10 and by retaining the thumb piece 10f in its depressed position, the 35 unit 38 and the supporting plate 10a may be bodily moved for a sliding movement parallel with the axis of the platen A and when the desired position is found, the release of the thumb piece 10f will permit the springs 10k—10k to 40 store the shoulders 10i—10i of the studs 10h—10h into the aligned enlarged openings 10j in the extension 10b of the ribbon spool plate 10 and retain the unit in adjusted locked position.

45 In adjusting the supporting plate 10a for the positioning of the unit 38 with respect to the type of ticket used, it will be noted, that the actuating arm 70 will move bodily therewith by means of the end 75 thereof extending through 50 the elongated slot openings 76 and 77 for actuating the unit and when the plate 10a is moved, the arm 70 will be carried by means of its contact with these slot openings 76 and 77 and cause a longitudinal sliding movement of the stud 71. 55 in the bushing 71a of the depending arm 70a. The sliding action of the arm 70 with respect to the depending arm 70a is permitted by means of the keyway 71b coacting with the bushing 71a, and in this manner the arm 70 is rockable 60 with the arm 70a with each operation of the machine regardless of the adjusted position of the unit 38 with respect to the type bars 25 of the adding machine.

65 The adjustment of the supporting plate 10a on the ribbon spool plate 10 also adjusts the rollers 19 and 20 fixed thereto near the free end thereof that support and guide the ribbon from the rollers 18 and 21 that are fixed to the ribbon spool plate 10. It will be noted that the adjustment of the unit 38 by means of depressing the thumb piece 10f will also adjust the length of the ribbon by means of the movement of the rollers 19 and 20 with the plate 10b, so that 70 upon adjusting the unit for various positions,

the ribbon 17 will be automatically adjusted therewith to be aligned in printing relation with respect to this unit 38 and also the type bars 25 of the adding machine.

In Figure 9, a partial detail view is shown of the ticket or slip on which the impressions of the unit and the type bars of the adding machine are made. The printing elements 51 of the unit print in the serial number comprising the first four numbers shown in this figure, 10 while the printing elements 50 mark the month and day, and the remaining characters on the ticket such as "C" and "6.00", are made by the type bars of the adding machine.

A unit of this type may be provided with sufficient characters depending upon its width so as to print more characters, for example the year, and while I have shown a plurality of printing elements, any number may be used with respect to the requirements to which a unit of this type 20 may be adapted without departing from the scope of the invention, and while I have illustrated and described my improved unit as being operable with an adding machine, the same 25 may be applied to other types of machines, or the device may be a separate unit embodying operating parts similar to those connected to the adding machine, and in such a machine it may be found desirable to omit some of the operating parts without departing from the scope of 30 the invention.

I claim:—

1. An auxiliary printing unit in combination with a platen or backing member adapted to receive the impact thereof, a base supporting 35 the unit, of printing elements carried on the unit, actuating means engaging said unit for movement therewith in one direction of its travel and to then disengage the same, means exerting an increased pressure to said traveling movement 40 of the unit whereby said unit will be carried in the reverse direction for an impact against the platen or backing member when said actuating means are released from engagement therewith and means on the unit yieldingly engaging the 45 base forming means for normally retaining the unit at retracted position, said last mentioned means being free of the base while said unit is moved by the actuating means.

2. A printing unit of the character described, 50 comprising a slidably mounted body, a plurality of printing elements carried on said body and extending outwardly of one end thereof, a base supporting the body for sliding movements thereon, impelling means normally urging said unit in 55 one direction, yieldable means on the unit co-acting with the base normally resisting said impelling means and retaining the unit in normal position, actuating means urging said unit in a direction against its impelling means, and to release the same, said yieldable means forming means for cushioning the unit when released from its actuating means.

3. In a printing unit of the character described, 65 the combination with adjustable printing elements employing a platen, of printing elements separate from and carried coaxially with the adjustable printing elements and operable to print digits aligned therewith on said platen, means adjusting the digit elements for a plurality of 70 successive positions, yieldable stop means, an impellent for the printing unit coacting with the yieldable stop means and normally retaining said unit retracted from the platen, and actuating means arranged to force said unit against its 75

impellent and to release the same to be impelled thereby for an impact against the platen, said unit having means thereon rendering the same readily engageable by the actuating means with each stroke thereof.

4. A printing unit of the character described, comprising a body member having an impellent to move the same in a path to coact with a platen, printing elements carried on the body member and normally retracted from the platen, an actuating means for said unit, an adjustable member normally in the path of and adapted to be engaged by said actuating means to cause the movement of said body member in one direction of its path of travel, said actuating means automatically disengaging said adjustable member and permitting said body member to be carried by its impellent for an impact of the printing elements against the platen, and manually controlled means associated with said adjustable member for rendering the same ineffective with said actuating means.

5. In a device of the character described, the combination with type carrying printing elements and a supporting frame therefor, a base on which the device is mounted for reciprocating movement away and toward a platen, of spring-impelled means for causing the movement of said frame and printing elements in one direction on said base, of actuating means for causing the movement of said device to exert a tension on said spring-impelled means and to be automatically disengaged therefrom, stop means including yieldable means coacting with the base whereby said device will be carried to normal position after said spring-impelled means have actuated the same for an impact against the platen, and means on the device forming means to carry said yieldable means therewith during its movements with the actuating means and for permitting said yieldable means to again coact with the base for retaining the device in normal position.

6. In an auxiliary printing mechanism, the combination with rotatable type carriers mounted to move in a path into printing relation with a platen, an impellent normally urging said printing mechanism toward the platen, engaging means causing a normal movement thereof against said impellent and to release the same for an impact against the platen, and means adapted to be manually actuated for rendering the printing mechanism inoperable with said engaging means.

7. A printing unit of the character described, the combination with a platen, of a spring-impelled body member adapted to move in a path, printing elements carried on the body member and adapted to coact with said platen and being normally retracted therefrom, an adjustable member carried on said body member, a tripping means adapted to engage said adjustable member to cause a given movement of said body member against the tension of its spring and to be automatically disengaged therefrom at the limit of its movement whereby said body member will be carried by its spring for an impact against said platen, and feed means coacting with said printing elements for adjusting them with each operation of the tripping means.

70 8. A printing unit of the character described, comprising type carrying elements having a supporting frame therefor mounted for reciprocating movements on an adjustable base and adapted to coact with a platen, spring means for causing the movement of said unit for an impact

against the platen, means for withdrawing said unit preparatory to the release thereof to effect printing impressions by an impact against the platen, and means for manually adjusting said adjustable base for selectively positioning the unit longitudinally of the platen.

9. The combination of claim 8 hereof in which there are means for sequentially adjusting some of the elements prior to the impact thereof against the platen.

10. The combination of claim 8 hereof in which an inking ribbon therefor is arranged to be adjusted in printing relation with respect to the positioning of the unit.

11. A printing unit of the character described, the combination with a platen, of type carrying elements having a supporting base therefor mounted for reciprocating movements on an adjustable base, yieldable means for causing the movement of said unit toward the platen, means for withdrawing said unit preparatory to the release thereof to effect printing impressions of the type carrying elements by an impact against the platen, means for manually adjusting said adjustable base for selectively positioning the unit longitudinally of the platen, and ribbon inking means having a portion thereof carried on and movable with said adjustable base whereby upon adjusting the unit longitudinally of the platen said ribbon inking means will be automatically adjusted therewith.

12. The combination of claim 11 hereof in which the adjustable base is provided with locking means for holding the unit in fixed adjusted position with respect to the longitudinal axis of the platen.

13. The combination of claim 11 hereof in which the means for withdrawing said unit is movable with the adjustable base while remaining in driving relation with the printing unit.

14. A spring-impelled printing unit adapted to coact with a platen or backing member and having a plurality of rotatable type carrying elements, rockable engageable means on the unit, of means for engaging the rockable engageable means for withdrawing the unit preparatory to the release thereof to effect a spring-impelled movement of said unit for an impact against the platen, and means for manually effecting a rocking movement of the rockable engaging means for preventing movement of the unit during successive operations of the withdrawing means; substantially as described.

15. A printing unit adapted to coact with a platen, comprising a body arranged to move in a path toward and away from said platen, printing elements carried on said body, means causing the movement of the unit away from said platen and automatically releasing the same, spring-impelled means coacting with said unit carrying the same for an impact against said platen when said last named means are automatically released, and feed means operable upon the movement of the printing unit causing a sequential change of some of the printing elements.

16. A printing unit of the character described, the combination with a platen arranged to back a record strip, of a body member adapted to move in a path with respect to said platen, printing elements supported on said body member and adapted to coact with said platen, means normally retaining said body member and printing elements in spaced relation with said platen, yieldable engageable means coacting with said

body member, and tripping means adapted to engage said yieldable engaging means to urge said body member a distance greater than its normal position from said platen whereby said 5 yieldable engageable means will urge the body member in the reverse direction for an impact of the printing elements against said platen when said tripping means is moved free thereof.

17. An auxiliary printing unit comprising a 10 frame supporting a plurality of rotatably mounted type carrying elements and adapted to move into printing relation with a platen, a base supporting the unit and having an elongated slot opening therein, yieldable means extending 15 through the elongated slot opening in said base normally retaining said unit in retracted position with respect to the platen, spring means co-acting with said unit urging the same in one direction, actuating means adapted to cause a 20 movement of said unit against the tension of the spring means and to be disengaged therefrom at the limit of its movement to permit the unit to be spring-impelled with its type carrying elements for an impact on the platen, said yieldable 25 means being arranged for a free movement with the unit during the movement of the unit against its spring means.

18. An auxiliary printing unit of the character described, comprising a slidably-mounted body 30 member having a plurality of adjustable printing elements thereon forming a unit in printing

relation with the platen of an adding machine, a base supporting the unit and having an opening therein, yieldable means extending through the opening of the base and normally withholding the unit retracted from the platen, spring means 5 normally urging said unit toward the platen, and tripping means connected to and operable by the driving mechanism of the adding machine for urging said unit against the tension of its spring means whereby said spring means will urge the 10 unit to cause the same to move beyond its yieldable means which is yieldingly engaging one end of the opening in the base and permit an impact of the printing elements against the platen as the tripping means is moved free of said unit. 15

19. An auxiliary printing unit of the character described, comprising a body member adapted to move in a path toward and from a platen and having adjustable printing units thereon, a base, an impellent urging the unit toward the platen, 20 engaging means causing a movement of the unit against said impellent and to release said unit for an impact against the platen, feed means operable upon the movement of the unit causing a 25 sequential change of said printing units, and spring means coacting with said feed means and base retaining said feed means readily operable and retaining the unit in spaced relation with the platen after the impact. 30

MAX GARBELL.
